UNITED STATES PATENT OFFICE.

CHARLES F. CLARK, OF CHICAGO, ILLINOIS.

HAT-FRAME FORMER.

No. 918,825.

Specification of Letters Patent.

Patented April 20, 1909.

Application filed May 23, 1908. Serial No. 434,558.

To all whom it may concern:

Be it known that I, CHARLES F. CLARK, citizen of the United States, residing at Chicago, in the county of Cook and State of Illinois, have invented certain new and useful Improvements in Hat-Frame Formers, of which the following is a specification.

This invention relates to formers for wire hat frames, and is shown applied to the hat frame former disclosed in the patent to George W. Price, No. 823,696, dated June 19, 1906.

The object of the invention is to provide improved means for supporting a greater number of notched rods for engaging the wires, permitting a wider range of adjustment, and producing a greater variety of shapes than with the machine shown in said patent.

20 The present invention has means for forming a high crown, especially; and for producing irregular shapes.

A further improvement over the original machine consists in a device for holding the 25 operating handle.

In the accompanying drawings, Figure 1 is a vertical sectional view showing supporting arms and adjusting rods on one side. Fig. 2 is a half plan view. Fig. 3 is a detail 30 in section showing the clamping bolt which holds the adjustable rods. Fig. 4 is an elevation and Fig. 5 is a section, in detail, of a clamping device for supporting the upper rods on the lower rods. Fig. 6 is a detail 35 of the device for holding the handle.

As shown in the patent referred to, the present machine has a post 1 with an upper fixed collar 3 and a lower sliding collar 2, which latter may be moved up and down by 40 the toggle lever 14 and connected arms, a coiled spring 9 forcing the lower collar down when released. The lower collar is pivotally connected to bent arms 4 the outer ends of which are connected by upper arms or 45 links 4^a to the upper collar. When the lever is swung up the arms are expanded, and when the lever is swung down the arms are contracted, in the manner disclosed in said patent.

50 For holding the lever handle in upper position I provide a catch bar 10 having near its outer end a notch 10^a and hinged at its lower end, as at 12, to a collar 11 at the base of the machine. When the lever is swung 55 up it may be caught in the notch 10^a as

shown in Fig. 6, and in dotted lines in Fig. 1, and the lever will be held in upper position until the catch bar is swung down and released. My invention also comprises means for supporting a plurality of the upright rods 5 by means of a single clamp. These rods 5 are notched at the top, as shown at 5^a, for the purpose of receiving the wires of the hat frame, and it is, of course, necessary that the rods be set in various positions to produce 60 different kinds of frames. The clamp for a plurality of rods consists of a bolt 8 adapted to extend through a slot 23 in the lower arm 4, whereby it may be moved to any position along said arm, and said bolt receives a plurality of blocks or disks 6 having the general 65 form of rather thick washers which will fit over the bolt under the head thereof, beside or against each other. Each disk has a groove or recess 6^a extending across one face 70 thereof and of proper size and shape to receive and hold the rod 5. These grooves or recesses are clearly shown in Fig. 3. A spring washer 7, under the head of the bolt 8, gives a yielding pressure, and enables the 75 rods to be turned or adjusted by special effort without necessarily loosening the bolt.

The disks 6 will turn on the bolt 8, and when they are turned the angles of the rods 5 will be varied accordingly. Also, the grooves 80 in the disks allow the rods to be adjusted up and down, whereby the position of the notches at the heads of the rods is varied. The disks when in position on the bolt co-operate with each other to form a clamp 90 which will hold all of the rods. But each disk is independently adjustable to vary the angle of the rod carried thereby, and each rod can be individually adjusted up or down as desired. For particularly high crowns, 95 extension rods 15 may be supported upon any one of the rods 5 by means of similar bolts and clamping disks, as shown in Figs. 4 and 5. The rod 5 is held by one disk and the rods 15 are held by others, all clamped 100 together by the same bolt, and capable of the angular and vertical adjustment above described. As an additional feature I also provide a cap 17 on the top of the standard 1, and this supports an adjustable center rod 19 105 which may be fixed at adjustment by a set screw 20. It is notched at the top to receive radial cross wires.

Obviously the machine may be used without the upper or extension arms 15, as they 110

may be readily detached by loosening the clamping bolt and slipping the clamp off the lower rod.

The machine so constructed will have a wide range of adjustment, permitting a large variety of shapes to be made.

The general manner of operation is the same as that described in the patent referred to and is sufficiently obvious from the above 10 description.

I claim:

The combination with a supporting arm of a hat-frame former, of a bolt extending

through said arm, a plurality of disks on the bolt, beside each other, each disk having a groove in one side to receive a rod, and a spring washer on the bolt, said disks and the washer being clamped together by the bolt, and the rods being held between the disks, in the grooves.

In testimony whereof I affix my signature, in presence of two witnesses.

CHARLES F. CLARK.
